(57) **CLAIM**

The ornamental design for a display screen or portion thereof with animated graphical user interface, as shown and described.

DESCRIPTION

FIG. 1 shows a first image of a display screen or portion thereof with animated graphical user interface showing our design;

FIG. 2 shows a second image thereof;

FIG. 3 shows a third image thereof;

FIG. 4 shows a fourth image thereof; and,

FIG. 5 shows a fifth image thereof.

The peripheral dashed broken lines illustrate a display screen or portion thereof, and form no part of the claimed design.

The appearance of the graphical user interface transitions between the images shown in FIGS. 1-5. The process or period in which one image transitions to another forms no part of the claimed design.

1 Claim, 5 Drawing Sheets
